UNITED STATES PATENT OFFICE.

FRIEDRICH GUSTAV STRITZEL, OF WASHINGTON, DISTRICT OF COLUMBIA.

FLUME-CLEANING APPARATUS.

1,110,408.

Specification of Letters Patent.

Patented Sept. 15, 1914.

Application filed April 29, 1913. Serial No. 764,394.

To all whom it may concern:

Be it known that I, FRIEDRICH GUSTAV STRITZEL, subject of the King of Prussia, German Emperor, residing at Washington, in the District of Columbia, have invented certain new and useful Improvements in Flume-Cleaning Apparatus, of which the following is a specification, reference being had therein to the accompanying drawing.

10 This invention relates to water flumes, of a character susceptible of general use, such as in connection with smelters, mills, factories, water-works, irrigation ditches, etc., and one of the primary objects of the invention is to provide a flume of the character mentioned having associated means designed to thoroughly cleanse the water of all floating and settling matter of a foreign nature, as the water passes to the usual 20 head gate of the flume.

Another important feature of the invention may be said to reside in the provision of novel and efficient means for preventing the customary "ice jams" in water flumes 25 during certain seasons of the year.

In the preferred embodiment of my invention, the last mentioned means is adapted to be moved out of operative position in the flume during the milder seasons of the year 30 when it is not necessary to provide against "ice jams."

It has heretofore been attempted, in the art, to cleanse the water in flumes in various ways, but none of the devices with which I 35 am familiar have proven thoroughly satisfactory, or gone into extensive use, among the objections thereto being the exceedingly complicated and expensive character of the constructions which render them impracticable to a large extent. Again, such prior constructions, most of which are run by water power, need a skilled operator or mechanic, in the operation thereof, parts of the construction often times getting out of 40 order, to such an extent as to destroy the usefulness, etc., whereas my present invention is of such a character that it is comparatively simple, inexpensive, durable and efficient, and it is readily operable by the ordinary workman, with the incident result that 45 the structure embodies a large saving in time, labor, and convenience in operation.

In the present embodiment of my invention, I arrange the various cleaning elements 50 in close succession in the flume adjacent the head gate thereof, the said elements being

sufficiently separated, however, one from the other, whereby the operation of one will not interfere with or impede the operation of the others, but coöperates therewith to thoroughly relieve the water of foreign materials, including both light and heavy, such as leaves, sand, etc.

In carrying out the principles of my invention I preferably provide the flume with an enlarged settling portion whereby the water in its passage through the flume is slightly impeded owing to the increased area at this point, thereby allowing the heavier foreign particles to sink into the settling tank, and in connection with the settling tank, I conveniently provide novel and improved means for exhausting the collected foreign matter at will.

The invention still further includes novel means adjacent one edge of the settling tank for guiding the heavier foreign matter in a downward direction or toward the tank, and suitable screening means adjacent the opposite edge of the tank, whereby to intercept any lighter floating particles which pass beyond the tank, and whereby to discharge said lighter particles, such as leaves, onto a support outside of the flume.

Various other improvements and novel details in the construction and arrangement of the several parts will be brought out more in detail in the description to follow, which, for a clear understanding of the invention, should be considered in connection with the accompanying drawing, forming a part hereof, and wherein is disclosed for the purpose of illustration, a convenient and satisfactory embodiment of the invention.

In the drawings:—Figure 1 is a top plan view of the device; Fig. 2 is a horizontal section; Figs. 3, 4, 5, 6 and 7 are detail views of parts removed.

With more particular reference to the drawings, wherein like reference numerals refer to corresponding parts throughout the several views, the flume preferably takes the form of a runway in which the water travels in the direction of the arrows, indicated in Fig. 1. The runway preferably comprises a bottom part 1 and side walls 2. At suitable intervals throughout the length of the flume I provide means for engaging ice and preventing the usual ice jams in a device of this character. While, as stated, a plurality of such means are provided, at suitable intervals apart, but one of such means is shown

for the purpose of illustration, and a description of one will suffice for the others. The means mentioned, for convenience termed ice combs, or stoppers, are in the form of a plurality of separated fingers 3, projecting from a transversely extending bar or rod 4 pivotally mounted at 5 in any desired manner to the sides of the runway. The fingers 3 are preferably stout or rigid prongs sufficiently long to penetrate the ice at the breaking up time in the spring of the year. Suitable means is provided for so supporting the fingers that they project into the water at an angle say of about 45 degrees, and with the free ends of the fingers slightly lifted, above the bottom of the runway. The supporting means in this embodiment of my invention takes the form of an elongated bar 6 projecting transversely across the runway, and loosely passing through apertures in the side walls 2 of the runway. It has a head 7 at one end whereby it may be engaged for removal at will and may have at its opposite end a releasable securing pin 8 passing through an aperture in the end of the bar. As stated, the bar when supported in the apertures on the side walls of the flume, will position the fingers 3 at an incline and in the path of the water, thereby serving as ice combs or stoppers preventing loose ice from coming together in sufficient quantities to cause a jamb.

When the ice season is over, it is desirable to move the fingers 3 out of the path of the flowing material in the conduit, and I may take advantage of the said bar 6 for this purpose. With this in view, the opposite sides of the runway have at the top a groove 9 adapted for the reception of the bar 6 when the latter is removed from the recesses intermediate the top and bottom of the sides. The supporting bar 4 having been swung about its pivotal connection, and the bar 6 having been positioned in the groove 9, at the top edges of the runway, the fingers 3 are permitted to fall into contact with the bar 6 where they are held out of operative position, until the time of the year when they are again needed. A suitable cord, chain, or the like of any desired construction, (not shown) may be employed for swinging the ice combs or stops about their pivotal connection, formed by the supporting bar, and in this same connection, the cord, chain or the like, by engaging a suitable retaining member on the flume, may serve to hold the fingers 3 in adjusted position, and this without the necessity of bringing into operation the supporting bar 6.

The flume is preferably enlarged laterally so as to provide a settling tank 10, the tank being of a size to impede the progress of the water through the flume at this point, to the end that the heavier impurities are allowed to settle in the tank. Preferably, the side

walls 10^a of the settling tank incline from their point of connection with the bottom 1 of the conduit, the said inclined sides 10^a being provided with radial ribs 36^a tending to direct the material toward the opening in 70 an elongated transversely extending receptacle 11 adapted for the reception of a suitable sand trap 12.

Arranged in advance of the settling tank 10 are a series of vertically extending loosely supported swinging prongs 13 preferably of wire. The prongs are arranged in a plurality of series, each series projecting downwardly from a transversely extending bar 14 bridging the 80 space between the sides 2 of the flume, and resting in receiving grooves 15 in said sides. The wires of each succeeding series are, as illustrated, arranged in staggered relation, and the action of these wires, which extend substantially from side to side of the runway in the path of the material with the lower end thereof slightly spaced from the bottom of the runway, is to create a suction downward and forward, thereby serving to deflect and lead the heavier flowing material, like slime, toward the bottom of the flume, so that the same will readily settle in the tank 10, to be received finally in the sand trap 12, together with the heavy rolling matter, such as sand, rocks, etc. From reference to Fig. 1 it will be observed that the wires 13 are shown in position, as acted upon by the water, whereas in Fig. 2, the wires are shown in substantially a vertical position 100 or at a time when they are not acted upon by the flowing material.

The sand trap proper, which has been given the numeral 12, is an elongated box-like receptacle conveniently of sheet or cast iron, the sides of which incline inwardly adjacent the top and then outwardly to provide flanges 12^a adapted to rest upon the inclined sides 10^a of the settling tank. The flanges 12^a terminate at a point below the top of the inclined sides 10^a, which is likewise below the bottom 1 of the flume. A suitable cover or closure 13^a is provided to form a top wall for the sand trap 12, the closure being adapted to fit between the inclined flanges 12^a of the trap and being pivotally connected at one side in any desired manner to one of the side flanges 12^a. The pivotal connection is indicated at 13^b, and it will be observed that this connection is of such a character that it forms a space 13^c between the closure 13^a and the connected flange 12^a to the end that when the top 13^a is slightly open, a return passage way 13^c is provided to allow settling of any sand which may have passed beyond the trap. One end of the sand trap 12 is provided with a suitable outlet 14^a adjacent the bottom thereof, which said outlet is adapted to be closed through the medium of any suitable valve, 130

- door, or other closure, that shown for the purpose of illustration taking the form of a swinging door 15' pivoted at 15^a to the wall of said open end, and adapted to swing as by a handle 15^b into and out of position to close the opening 14^a. In order to make this closure a water tight one, a suitable packing, as a layer of felt, may be provided, on the inner surface of the door. The top 5 13^a is preferably moved about its pivotal connection 13^b through the medium of suitable chains 16, connected at one end as by rings 17, to the top 13^a, and at the opposite end to a suitable pulley 18 mounted on a 10 shaft 19 having a suitable bearing at opposite ends in the side walls 2 of the flume. The said shaft 19 is mounted for rotary movement and to this end I provide a handle 20 connected at one end to the shaft 19, and in order to hold said shaft together with the chains and the top 13^a, in adjusted positions, a suitable cog wheel 21 is arranged on the shaft and a spring held locking dog 22 mounted adjacent the side wall of the 15 flume, serves to engage the cog wheel and hold the same in position. The top 13^a is also provided with an opening 23 adjacent the forward end thereof. In the normal position of the top 13^a in order to receive 20 the sand and the other heavier particles, the free edge assumes a position whereby the same is open or slightly above the height of the bottom of the flume. In this way, the sand and other heavier particles drop into 25 the open receptacle or sand trap 12. Now as it becomes desirable to cleanse the receptacle 12, the top 13^a assumes a closed position, and the closure 15' is moved to open position with the result that the water 30 passing into the opening 23 at the forward end of the top will force the dirt out through the opening 14^a at the opposite end of the receptacle. In this way, the sand trap will be thoroughly cleansed. 35 Having run through the tank, the water again enters the reduced area of the flume, and at this point, I provide a screening member. The screen proper takes the form of a suitable frame 23' or border into which 40 the screen is laid, a screen netting of galvanized wire 24 having proven highly satisfactory for this purpose. The screen material may be secured to its border in the following manner: A reinforcing bar 23^a projects 45 over the screen at each side of the border, and U-shaped clips 23^b overlie said bars. The arms of the clips are threaded and pass through suitable apertures in the border and are secured in place by nuts 23^c. In this 50 way the bars and the screen are firmly supported in position. The screen is suitably reinforced at points between the border as by stay bars 24^b extending in different directions, and assume a position at an incline 55 upwardly and rearwardly from the lower 60 edge thereof, the border 23' being obviously mounted in any desired manner as at 25 to the side walls 2 of the flume. Suitable rest bars 26 project between the sides of the flume to support the screen 70 against the weight of the running water. The screen is of relatively fine mesh and of a size to intercept the passage of leaves and other lighter foreign matter through the flume. The screen is light in construction 75 whereby it may be readily moved, and in order to move the same into and out of operative position in the flume, the pivoted end of the border 23' is provided with a suitable gear wheel 27 in engagement with a drive pinion 28 mounted on a stub shaft 29 secured to the side of the flume, the pinion 29 being adapted to be rotated by a handle 30. A suitable support is provided for the screen when the latter is moved out 80 of the path of the flowing material in the flume, the said support comprising a substantially U-shaped abutment bar 31, the opposite arms thereof in the form of tubular members 32 being adapted to interengage or telescope with suitable tubes 33 supported from the top edges of the flumes, as by brackets 34 and 34^a. The tubes extend in a direction forwardly at an incline whereby to position the transversely extending rest bar 31 slightly to the rear of the pivotal connection 25 for the screen, to the end that as the screen is moved about its pivotal point upwardly, the same, after passing its center, will fall by gravity into 90 100 contact with the rest bar. In order to protect the parts against injury, the rest 31 is yieldable, through the medium of a spring 35 interposed between the tubular members 32 and 33, as clearly illustrated in Fig. 6. 105 The flume to the rear of the screen may be covered, as shown at 36, which said covered portion forms a receiving receptacle for the leaves and other lighter foreign matter which may come into engagement with the 110 screen netting 24. In this connection, the screen netting forms, with the surrounding side border, a shovel like construction whereby in the swinging movement thereof, about its pivot, the material is lifted and 115 deposited onto the platform formed by the cover 36 of the flume. 120 From the description, it is believed that the operation of the apparatus will be obvious to those skilled in the art. At such times of the year when it is necessary to provide against ice jams, the ice combs 3 assume the position illustrated in Fig. 2 of the drawings. When, however, the seasons change, the supporting bar 6 assumes 125 a position in the grooves 9 in the upper edges of the sides of the flume, thereby positioning the ice combs out of the path of the flowing material. The material as it flows along the runway is brought into 130

contact with the plurality of closely associated wire fingers 13, which latter tend to force any foreign matter toward the bottom of the flume, and create a slight suction at 5 this point, whereby the foreign matter readily settles into the tank 10. The top of the sand trap being open to a point in substantial alinement with the bottom of the flume, the sand and other foreign particles 10 find a passage through the open top of the receptacle 12 into said receptacle from whence the same may be discharged through the outlet 14^a. When the top is closed, the water finds a passage through the opening 15 23, thereby forcing the material through the outlet 14^a, the closure 15 having been moved to open position. Such lighter foreign material as passes beyond the settling tank and does not return into the receptacle 12 20 through the hinge opening 13^b, gradually accumulates onto the shovel-like screen by which it is carried into a depositing position by rotating the handle 30, and bringing said screen into contact with the abutment 31.

Various minor changes may be made in the details of the construction without departing from the spirit of my invention as herein described, and set forth in the accompanying claims.

I claim:—

1. In a water flume, and in combination, a pivotally supported manually operable trash collecting and removing screen arranged 35 normally within and across the flume, and inclined forwardly, means for swinging the screen upwardly on its pivot thereby carrying the collected material on the face of the screen out of the flume, and means in the 40 flume immediately in advance of the screen for collecting and preventing accumulation of non-floating substances on the lower edge of the screen.

2. In a water flume, and in combination, a pivotally supported trash collecting and removing screen arranged normally within the flume at a forwardly inclining angle, the lower forward edge of the screen being adjacent the bottom of the flume, manually 50 operable means for swinging the screen upwardly thereby carrying the collected material out of the flume, a settling chamber in the bottom of the flume in advance of the screen, said settling chamber being constructed and arranged to collect and prevent 55 the accumulation of sand and the like adja-

cent the lower edge of the screen whereby the screen may be readily elevated and means arranged in advance of the screen for intercepting large bodies and preventing the same from accumulating on the screen, substantially as described.

3. In a flume and in combination, a swinging screen, pivotally supported at its upper end above the flume and having its body part located within the flume at an angle, means for swinging the screen upwardly, a floor in the rear of the screen, and a stop arranged rearwardly of the pivotal point of the screen whereby when the screen engages the stop, the material collected on the screen will be deposited on the floor, substantially as described.

4. In a flume, and in combination, a pivotally supported screen extending into and across the flume at a forward incline, means for swinging the screen forwardly on its pivot, a yielding stop arranged rearwardly of the screen, and in the path of the screen as it swings on its pivot whereby the material lodged on the face of the screen will be dislodged therefrom, and a collecting surface arranged below the stop.

5. In a flume, and in combination, a swinging screen pivotally supported at its upper edge above the flume and having its body part projecting into and across the flume at a forward incline, a stop arranged above the flume and in the rear of the pivotal connection for the screen, said stop comprising a cross bar and yielding means for maintaining the cross bar in normal position and a surface below the stop for collecting material dislodged from the screen upon its contact with the stop.

6. In a flume and in combination, a swinging screen, pivotally supported at its upper end above the flume and having its body part located within the flume at an angle, gearing for swinging the screen upwardly, a floor in the rear of the screen, and a stop arranged rearwardly of the pivotal point of the screen whereby when the screen engages the stop the material collected on the screen will be deposited on the floor, substantially as described.

In testimony whereof I affix my signature in presence of two witnesses.

FRIEDRICH GUSTAV STRITZEL.
